SOLE COMPRESSOR FOR SHOES

Charles J. Simonetti, Brooklyn, N. Y.

Application March 30, 1942, Serial No. 436,778

1 Claim. (Cl. 12—124)

This invention relates to novel mechanism and arrangements for compressing soles in the manufacture of shoes.

In accordance with my present invention, I provide a sole compressor machine incorporating a "jack" or last upon which the shoe is readily fitted and demounted. The sole compressing operation occurs at an intermediate stage in the manufacture of the shoes. With the system of my present invention, the second lasting operation, prior to the sole compression, is entirely dispensed with. Thus, the time consumed in mounting the shoes upon the second last and then stripping it off after the sole compression operation, is saved, reducing the cost of the shoe manufacture. Also, the investment in the lasts requisite for the corresponding prior art operation is obviated. The invention is particularly applicable to the manufacture of slippers, playshoes, and regular shoes, reducing the manufacturing cost thereof.

The above and other advantages, capabilities and objects of my invention will become more apparent in the following description of a preferred form for practicing my invention illustrated in the following drawings, in which:

Fig. 1 is an end view of a sole compressor machine in accordance with my present invention.

Fig. 2 is a front view of half of the machine of Fig. 1.

Fig. 3 is a perspective illustration of the shoe jack mounted upon the sole compressor, in the operative position.

Fig. 4 is a perspective illustration of the shoe jack of Fig. 3, in position for inserting a shoe, preparatory to the sole lasting operation.

Fig. 5 is a vertical cross-sectional view through the shoe jack, taken along the line 5—5 of Fig. 3.

Figs. 6 to 8 show details of a preferred embodiment of the shoe jack.

Referring now more particularly to the drawings, Figs. 1 and 2 illustrate the sole compressing machine incorporating the invention jack. The machine comprises a yoke 10, mounted on a pedestal 11, supported on base 12. The shoe jack or last 15 extends from a bar 16, pivoted at 17 in yoke 10. The elevation of bar 16 is adjusted through hand wheel 18, connected to a threaded rod 19, the end of which is coupled to a block 20. Block 20 rides in channel 21, 21 of bar 16, and is coupled to rod 19 through universal coupling 22. The elevation of bar 16 is adjusted in accordance with the length and size of last 15 supported above the machine bed.

The sole compressor machine includes a blad-

der 23 extending above the base 24 of the unit. The bladder may be of leather, rubber or the like. The bladder is inflated to provide pressure for the sole compressing operation for the purpose hereinafter to be described. The inflation of bladder 23 is accomplished when the operator depresses foot pedal 25. Depression of pedal 25 actuates lever 26 which in turn controls an air valve (not shown), which fills bladder 23 with compressed air, and presses it against the bottom of jack 15 in a manner known to those skilled in the art.

An important feature of the present invention resides in its adaptability for materially facilitating the operation of sole compressing in the manufacture of shoes. The shoe is fitted on to the universal type jack 15. Towards this end, jack 15 is provided with a hinge or similar pivotal arrangement 27 to permit its extension away from the vertical plane to the dotted position 15' shown in Fig. 2. The vertical position of jack 15 corresponds to the sole compression position. After the shoe is inserted upon the jack 15 when in the extended position 15', the jack bearing the shoe is returned to the vertical position. Hand wheel 18 has previously been adjusted so that bar 16 is at a proper angle to hold jack 15 and a shoe thereon contiguous with bladder 23 when the jack is in a vertical position. A pad 28 shown in Fig. 1 is preferably used beneath the rear or heel portion of the jack or shoe to afford a continuous pressure actuation against the shoe during the sole compression operation. By pressing on foot pedal 25, the bladder 23 is inflated to bear against the sole of the shoe mounted on jack 15 when in vertical position, to afford a uniform pressure of sufficient intensity against it. The hinged or pivoted arrangement of jack 15, to be described in more detail hereinafter, is such as to permit a sustained pressure in a vertical plane or direction. After the compressing operation, the jack 15 is pivoted upwardly to position 15', and the compressed shoe removed therefrom. Another shoe is then placed on the jack and the cycle of operations herein described is repeated.

In the manufacture of shoes of a certain type, the shoe platform is McKay stitched to the shoe body. Such operation requires the original shoe last to be removed. Heretofore it was then necessary to replace the last in order to continue with the sole mounting and compressing operations. The present invention, as hereinabove set forth, eliminates this second relasting operation in the following manner. The McKay stitched platform is cemented and dried. The sole to be

adhered to the platform is also cemented and dried. The sole is then spotted with glue or cement to its position on the platform. The shoe with the sole spotted thereto is then inserted onto the jack 15, when in the raised position 15'. The jack is then put in the vertical or compression position and the sole compressed directly thereon under the high pressure provided by the extension of bladder 23 with the compressed air. After the compression the shoe is removed by turning the jack to the outside position 15'. The operation is then continued successively with other shoes and without requiring relasting thereof. Thus, the number of lasts required in the manufacture of shoes is cut in half, since the second lasting is eliminated.

Figs. 3 and 4 are enlarged perspective illustrations of a preferred form for the construction of jack 15. Jack 15 extends from a flat bar portion 30 connected to a fastening element 31 through hinge 27. Bar portion 30 extends to a position beyond the hinge 27 connection to form a projection 32. Thus, a type of hinged arrangement is formed which permits the jack 15 to sustain a tremendous vertical pressure in the shoe compressing operation without twisting from its vertical alignment. When the bladder 23 is in the deflated condition, the jack 15 may be manually twisted away from the vertical position to that shown at 15' in Fig. 2 and in Fig. 4. A shoe may be readily put on or removed from the jack when in the extended position referred to. The jack 15 is connected to the service bar 16 through connecting piece 31 which is in the form of a U-member, containing openings through which a pin 33 extends. A cotter pin 34 at the open end of pin 33 secures the connecting piece 31 at a desired opening 35 in bar 16. Jack 15 may accordingly be located in any desired position with respect to bladder 23 on the sole compressor machine. The slope of bar 16 is adjusted through hand wheel 18 in accordance with the corresponding slope on the surface of bladder 23.

Jack 15 is provided with an adjustable sole member 36 so that one jack may be used for several shoe sizes. The bottom section 37 of jack 15 generally conforms in shape to the type of shoe it is used for. However, the rear section 38 is made a little narrower than the actual shoe to facilitate the ready mounting and demounting of the shoe on the lasts. I have found that the small discrepancy between the bottom surface 37 of the last with respect to the actual inner surface of the shoe does not affect the uniformity and quality of the sole compression therewith. Also, by extending the sole section of the last through sole member 36, a larger size shoe is readily accommodated by the machine. Furthermore, the intermediate or blank space 39

formed when sole section 36 is extended, does not affect the compression result. Thus, one, two or three jacks of this type may be employed for a whole line of shoe sizes. Production can therefore proceed with negligible handling or replacing of jack 15.

Fig. 5 is a cross-sectional view through the last, illustrating how the stable adjustments as to the extension of sole portion 36 are performed. Sole member 36, as seen in Figs. 5 and 7, has a central projecting rib 40 to which a rectangular plate 41 is secured by screws 42, as seen in Figs. 3, 5 and 7. Rib 40 rides in a channel 43 in the bottom of jack 15; and plate 41 rides in a contiguous wider channel 44 within jack 15. A set screw 45 is threaded into the central body portion of jack 15 and turned against top surface of plate 41, to hold the sole extension member 36 in any desired adjusted position. Actual shoe sizes may be marked by scale 46 on the extending surface of plate 41 and rib 40, as shown in Figs. 3 and 7, to facilitate adjustment to a desired shoe size. Scale 46 is read at the contiguous last edge 47, shown in Fig. 3. Instead, a scale may be marked on the underside 39 of the last as shown at 48 in Figs. 4 and 6.

An extension member 50 may be mounted on jack 15, as shown in Fig. 8. The purpose of member 50 is to adapt the jack for shoes of even longer size than adjustments of sole extension 36 effect. Member 50 has a flat bottom surface which is in the plane of bottom 37 of the jack. Two pins 51 extend from member 50 into sockets 52, incorporated in the corresponding jack end.

Although I have disclosed a preferred embodiment for carrying out my present invention, it is to be understood that changes may be made therein falling within the broader scope thereof, and accordingly I do not intend to be limited except as set forth in the following claim.

What I claim is:

A shoe jack comprising a body portion having a sole shaped portion and a heel portion, a member adjustably extensible from said sole portion for increasing the shoe size of the jack, said member containing a longitudinal rib, a plate secured longitudinally of said rib, said plate and rib being fitted into a corresponding T-shaped channel in said body portion and said plate supporting said member on said body portion, means for securing said plate and said member to said body portion in their adjusted position, said heel portion having a pair of longitudinally extending recesses therein, and a heel member selectively connectible to said heel portion for increasing the shoe size of the jack, said heel member having a pair of pins engageable in said recesses.

CHARLES J. SIMONETTI.
